UNITED STATES PATENT OFFICE.

LOUIS AARON LEBOWICH, OF BOSTON, MASSACHUSETTS.

FILING-CASE FOR CARDS AND THE LIKE.

1,079,776.

Specification of Letters Patent.

Patented Nov. 25, 1913.

Application filed April 26, 1913. Serial No. 763,939.

To all whom it may concern:

Be it known that I, LOUIS AARON LEBOWICH, a citizen of the United States, residing at Boston, in the county of Suffolk and 5 State of Massachusetts, have invented certain new and useful Improvements in Filing-Cases for Cards and the like, of which the following is a specification.

My invention relates to filing cases for 10 cards and the like and has for its object to provide an improved filing case of this class.

The invention consists of a filing case for 15 cards and the like comprising a box or receptacle within which is arranged a vertically disposed follower slidably connected through a clamp with one or more bars or strips near the bottom of said box or receptacle. This clamp is operated by a lever that is pivotally mounted on the follower 20 and controlled by an upright slide also mounted on the follower, preferably in such fashion that when the slide occupies its lowermost position the clamp grips the bar or strip so as to hold the follower in a fixed 25 position within the box or receptacle and when said slide is shifted into its uppermost position it acts through said lever to operate the clamp and free the follower from said strip or bar.

Other features of my invention are hereinafter pointed out.

In the accompanying drawings: Figure 1 is a cross sectional view of a file for cards and the like constructed in accordance with 35 this invention. Fig. 2 is a plan view of the parts shown in Fig. 1. Fig. 3 is a side view of the follower shown in Fig. 1 with the parts in the same position. Fig. 4 is a partial sectional view of the file shown in Fig. 40 1 but showing the parts in different positions. Fig. 5 is a sectional view on line 5-5 of Fig. 4. Fig. 6 is an enlarged side view of one of the bars or strips hereinafter referred to.

Having reference to the drawings, A represents the box or receptacle; B the follower mounted therein; C the clamp operating lever; and D the lever controlling and operating slide.

The bottom of the box A is made with a longitudinal slot a at each side of which is a metal bar a' fastened to the bottom of said box by screws a''. These bars a' over-

hang the edges of the slot a so as to leave lips or tongues to coöperate with the spring clamp to be described. The spring clamp comprises a fixed member in the form of a plate e mounted to slide on top of the bars a' and having fixed to its underside a bolster plate or block e' to the underside of which is fastened a leaf spring e'' whose free end e''' serves as a spring pawl to engage the undersides of the bars a'. This spring pawl e''' is constructed and arranged so that it normally tends to press against the underside of the bars a' and by such pressure cause the said bars to be gripped between said pawl and the plate e to hold the follower B against longitudinal movement on the bars a'. The plate e is made with an upturned end e⁴ fastened by rivet e⁵, or otherwise, to the follower B which latter is made from a piece of sheet metal. The lever C is fulcrumed at c on the upturned end e⁴ of plate e and is made with an arm c' 65 projecting downward between bars a' into position to coöperate with the top side of the spring pawl e''' and with an upwardly extending arm c² provided at its upper end and upon the inner side thereof with a stud c³ made with a head c⁴, said stud extending through an inclined slot d provided in the lower end of the slide D with the head c⁴ at the inner side of slide D so that said stud cannot be sprung accidentally or otherwise 85 out from the slot d. The slide D extends to the top of the follower B and is provided with a vertical slot d' occupied by studs d² projecting from follower B which hold said slide to the follower with provision for limited up and down movement of the slide. The upper end of slide D extends slightly beyond the top of B and is made with a finger notch d''.

With the parts in the positions shown in Fig. 1 the spring clamp is locked to the bars a' and acts to hold the follower B against movement on said bars. It will be plain, however, that by grasping the upper end of slide D and pulling said slide upward cam slot d acts through stud c³ to swing lever C on its fulcrum c in a direction to throw the arm c' downward. When arm c' is thus thrown downward it engages the spring pawl e''' and forces the latter away from bars a' thus freeing follower B from said bars so

that it can be shifted within the box A as 5 may be desired. In the best form of my invention the undersides of the bars a^3 are made with rack teeth a^3 as shown in Fig. 6 so that the follower B is positively held against rearward movement under pressure from the contents of the box.

As will be clear from the foregoing description all of the parts of my improved 10 file except the box A and the rivets, studs and screws, are made from sheet metal arranged side by side so that said sheet metal parts are not only strong and durable but they occupy a minimum amount of space, 15 which, of course, provides more room in the box A to receive cards or the like. Another advantage to the construction disclosed is that the slide D occupies its lowermost position when the spring clamp is in 20 its set condition and therefore not only is the top of said slide down out of the way but gravity tends to hold it in that position and the normal condition of the parts controlled by the slide can be disturbed only 25 by intentionally operating the slide D.

Having described my invention, what I claim as new and desire to secure by Letters Patent is:

1. A filing case for cards and the like 30 comprising a receptacle provided near its bottom with a bar; a follower arranged within said receptacle; a clamp carried by the follower and coöperating with said bar; a lever pivotally mounted on said follower 35 for operating said clamp and an upright slide mounted on the follower for operating said lever.

2. A filing case for cards and the like 40 comprising a receptacle provided near its bottom with a bar; a follower arranged within said receptacle; a spring clamp carried by the follower and normally tending to engage said bar so as to hold the follower against movement within the receptacle; a 45 lever pivotally mounted on the follower for operating said clamp and an upright slide mounted on the follower for operating said lever.

3. A filing case for cards and the like 50 comprising a receptacle provided near its bottom with a bar; a follower arranged within said receptacle; a clamp on said follower and coöperating with said bar; said clamp comprising a spring pawl engaging said bar 55 to hold the follower against movement within the receptacle; a lever pivotally mounted on the follower in position to coöperate with said spring member and an upright slide mounted on the follower through upward 60 movement of which the lever is operated to disengage the spring member of the clamp from said bar.

4. A filing case for cards and the like comprising a receptacle provided near its bot-

tom with a slot; two bars secured to the bottom of said receptacle; one at each side of said slot and each overhanging said slot so as to provide said slot with two inwardly projecting lips; a follower arranged within said receptacle provided at its lower end 70 with an extension projecting into said slot; a spring pawl fastened to the underside of said extension and coöperating at its free end with the undersides of said lips; a lever pivotally mounted on said follower in position to coöperate with the free end of said spring pawl and provided with a stud on one arm thereof and an upright slide mounted on the follower and made with a cam slot into which projects the stud on said lever. 80

5. A filing case for cards and the like comprising a receptacle provided near its bottom with a slot; two bars secured to the bottom of said receptacle, one at each side of said slot and each overhanging said slot so 85 as to provide said slot with two inwardly projecting lips; a follower arranged within said receptacle provided at its lower end with an extension projecting into said slot; a spring pawl fastened to the underside of 90 said extension and coöperating at its free end with the undersides of said lips; a lever pivotally mounted on said follower in position to coöperate with the free end of said spring pawl and provided with a stud on 95 one arm thereof and an upright slide mounted on the follower and made with a cam slot into which projects the stud on said lever; the cam slot in said slide being constructed so that upward movement of the slide operates the lever so as to cause the latter to shift the spring pawl out of engagement 100 with said lips.

6. A filing case for cards and the like comprising a receptacle provided near its bottom with one or more bars provided on its underside with rack teeth; a follower arranged within said receptacle provided near its lower end with a clamp coöperating with said bar; said clamp comprising a spring 110 pawl to engage the teeth on said bar; a lever pivotally mounted on said follower in position to coöperate with the spring pawl and an upright cam slide on the follower coöperating with said lever. 115

7. A filing case for cards and the like comprising a receptacle having its bottom made with a slot; two bars fastened to said bottom, one at each side of said slot so as to overhang the latter and provide two lips, 120 one at each side of the slot; said bars being provided on their undersides with rack teeth; a follower arranged within said receptacle and provided at its lower end with an extension projecting between said bars; a spring pawl secured to the underside of 125 said extension and arranged so that its free end coöperates with the rack teeth on said

bars; a lever pivotally mounted on the follower and coöperating with the free end of the spring pawl; said lever being made with an arm provided with a stud and an upright slide mounted on the follower and made with a cam slot into which said stud projects.

In testimony whereof I have affixed my signature, in presence of two witnesses.
